UNITED STATES PATENT OFFICE.

JOHN T. HOGAN, OF DENVER, COLORADO, ASSIGNOR OF ONE-HALF TO PETER KLINKHAMMER, OF LOS ANGELES, CALIFORNIA.

HOOP LUG AND CONNECTION.

No. 922,767.

Specification of Letters Patent.

Patented May 25, 1909.

Application filed June 29, 1908. Serial No. 441,019.

To all whom it may concern:

Be it known that I, JOHN T. HOGAN, a citizen of the United States, a resident of the city and county of Denver, State of Colorado, temporarily residing at Los Angeles, in the county of Los Angeles and State of California, have invented a new and useful Hoop Lug and Connection, of which the following is a specification.

10 The object of this invention is to provide superior means of very simple and inexpensive construction for connecting the ends of the band of adjustable hoops on tanks and other circular vessels, whereby the force applied to tighten the band will operate more fully to draw the ends of the band together, than with the construction heretofore employed.

15 The invention includes the improved means for connecting said ends of the band, and also the improved means for drawing said ends toward each other.

20 A further object of the invention is to provide superior means whereby the connecting appliance may be attached to the ends of the hoop bands in the most convenient and ready manner without any liability of slippage.

25 Another object is to make provision whereby the band and the parts directly connected thereto in the present application of this novel connecting appliance will not interfere with the operation of the parts by which the tension is applied to the band.

30 The accompanying drawings illustrate the invention.

Figure 1 is a view of the invention as applied in a hoop on a tank, fragments of the hoop and tank being shown. Fig. 2 is a longitudinal section of parts shown in Fig. 1.

35 1, 1' designate the ends of a band of the usual character which forms the main encircling body of the hoop.

40 2, 2' designate two lugs each of which comprises a transversely-slotted base 3 and an eye 4. The perforation 5 of the eye extends longitudinally, and the recess 6 extends between the slot 7 and the end of the base opposite the eye, and on the opposite side of 50 the base from which the eye projects.

45 8 designates strengthening ribs at the sides of the base.

9 designates a recess adjacent the eye 4 to accommodate the tightening nut 10.

55 11 designates a flexible screw-threaded con-

nection the terminals of which extend through the eyes 4, 4'.

The nuts 10, 10' are screwed onto the ends of the flexible connection to force the lugs toward each other. The ends of the band 60 are respectively bent onto the lugs by inserting each end through the slot of its lugs and bending it about the bar 12 of its lug, the recess between the slot and the end of the lug accommodating the indent portion of the 65 band. The indent portion of the band may be of any required length so that in practical operation the workman may simply insert the end of the band through the slot such a distance as to bring the eyes of the lugs at an 70 appropriate distance apart when the band is brought to proper position on the tank or other vessel to be hooped.

One end of the flexible connection may at the outset be secured to one of the lugs, the 75 other end of the flexible connection being left free and without its nut so that it may be inserted through the eye of the other lug when the band has been brought into position on the tank. The workman may hammer the band flat at the bent places, and when the band is in proper position on the tank, may insert the free end of the flexible connection through the eye that is to receive the same; the nut being brought into position in its recess, and turned to screw it onto the free end of the flexible connection. Then one or both of the nuts may be tightened as required to draw the lugs toward 80 each other, thereby tightening the hoop. 85 The flexible connection may be made of two parts a, b, hinged or jointed together in the middle, as shown in Figs. 1 and 2, or it may be constructed in some other fashion but flexible in the middle. When the nuts are 90 tightened, the force is thus exerted in a direction most effective to draw the ends of the band together and entirely without the opposing forces that operate when a straight or rigid bolt is used; such a bolt applying 100 the force used in a different tangent from the direction of the hoop, and the force so exerted is opposed by the transverse pull of the tightening hoop on the middle of the straight bolt heretofore employed. 105

The orifices 5 of the eyes are of considerable length, and the portions of the flexible connection which extend through said eyes are preferably rigid so that they will move freely axially in the perforation. In the 110

preferred form, the flexible connection is formed of a plurality of members and is provided between the rigid shanks with a joint which is in the middle of the connection.

5 In this way the tendency to bend the members in or at the margin of the orifice of the eye is minimized.

It is evident that various means may be employed for fastening either end of the 10 flexible connection, the other end being provided with the adjustable fastening means as the nut, but it is best to provide both ends with nuts as shown.

I claim:—

15 Means for connecting the ends of a hoop, the same comprising two lugs each having a transverse slot at one end through which the

end of a hoop can be inserted and doubled under and thus pressed against the tank or cylinder, the other end of each lug having a 20 protuberance provided with a longitudinal eye, two threaded eye-bolts the eyes of which are interlocked and the shanks of which extend through the longitudinal eyes respectively, and nuts screwed on the bolts to 25 draw the lugs toward the interlocked eyes.

In testimony whereof, I have hereunto set my hand at Los Angeles, California, this 19th day of June, 1908.

JOHN T. HOGAN.

In presence of—

JAMES R. TOWNSEND,
M. BEULAH TOWNSEND.
